(57) **CLAIM**

The ornamental design for a T-shirt ruler, as shown and described.

DESCRIPTION

FIG. 1 is a front and top perspective view of a first embodiment of a T-shirt ruler, showing my new design; FIG. 2 is a rear and bottom perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is a front and top perspective view of a second embodiment of the T-shirt ruler; FIG. 10 is a rear and bottom perspective view thereof; FIG. 11 is a front view thereof; FIG. 12 is a rear view thereof; FIG. 13 is a left side view thereof; FIG. 14 is a right side view thereof; FIG. 15 is a top view thereof; FIG. 16 is a bottom view thereof; FIG. 17 is a front and top perspective view of a third embodiment of the T-shirt ruler; FIG. 18 is a rear and bottom perspective view thereof; FIG. 19 is a front view thereof; FIG. 20 is a rear view thereof; FIG. 21 is a left side view thereof; FIG. 22 is a right side view thereof; FIG. 23 is a top view thereof; FIG. 24 is a bottom view thereof; FIG. 25 is a front and top perspective view of a fourth embodiment of the T-shirt ruler; FIG. 26 is a rear and bottom perspective view thereof; FIG. 27 is a front view thereof; FIG. 28 is a rear view thereof; FIG. 29 is a left side view thereof; FIG. 30 is a right side view thereof; FIG. 31 is a top view thereof; and, FIG. 32 is a bottom view thereof.

The broken lines in the figures illustrate portions of the T-shirt ruler that form no part of the claimed design.
